UNITED STATES PATENT OFFICE.

HENRY H. ASHLOCK, OF CLYDE, KANSAS.

HYDROCARBON-BURNER.

SPECIFICATION forming part of Letters Patent No. 734,152, dated July 21, 1903.

Application filed December 23, 1902. Serial No. 136,389. (No model.)

To all whom it may concern:

Be it known that I, HENRY H. ASHLOCK, a citizen of the United States, residing at Clyde, in the county of Cloud and State of Kansas, have invented a new and useful Hydrocarbon-Burner, of which the following is a specification.

This invention relates to hydrocarbon-burners; and it has for its object to provide a device of this class which may be quickly and conveniently applied to be used in connection with either cooking or heating stoves of ordinary construction.

My present invention has for its object to produce a burner of this class which shall be simple in construction, effective in operation, and in which air supplied through openings in the top plate or cap shall be used for the purpose of supplying the necessary draft to support the combustion of the liquid fuel supplied to the base or pan of the burner.

With these and other ends in view my invention consists in the improved construction, arrangement, and combination of parts which will be hereinafter fully described, and particularly pointed out in the claim.

In the accompanying drawings, Figure 1 is a perspective view of a hydrocarbon-burner constructed in accordance with the principles of my invention and illustrating the preferred form of the same. Fig. 2 is a vertical sectional view showing the preferred form of my improved hydrocarbon-burner in position for operation in connection with an ordinary cook-stove. Fig. 3 is a vertical sectional detail view taken at right angles to the device, as shown in Fig. 2.

Corresponding parts in the several figures are indicated by similar characters of reference.

My improved hydrocarbon-burner partakes of the nature of a pan, basin, or receptacle, such as 1, which may be of any desired size and shape and which is supported by the lower end of a tubular supporting device 2, the walls of which are provided with a plurality of slots, such as 3, which may be of any desired width and which constitute the slits through which in practice the flames are projected. The supporting-tube or burner-tube 2 is provided at its upper edge with an outwardly-extending annular flange 4, where-

by it may be supported in position for operation in the griddle-hole of an ordinary cook-stove or in a supporting-plate disposed for its reception in any suitable position or location. The said supporting-tube or burner-tube is also provided at its upper edge with an interiorly-disposed annular shoulder 5, adapted to support a top plate or cover 6, which is provided with a plurality of openings 7 for the admission of air to support combustion. The feed-pipe 8, which is provided with a valve 9, whereby the supply of fuel may be regulated, extends through an opening 10 in the top plate or cover 6, where the said feed-pipe may be secured, if desired, in any suitable manner, so as to be permanently supported. Preferably, however, the said feed-pipe is independently supported by means of suitably-disposed brackets 11, which render it independent of the top plate of the burner.

The base-pan 1 is extended laterally from the lower end or edge of the supporting-tube, as clearly shown in Figs. 1 and 2 of the drawings, where the burner is thus illustrated as being practically L-shaped.

In practice the burner-pan or fuel-pan 1 is provided with a layer of absorbent material, which may be readily saturated by the oil which passes through the feed-pipe to the said pan. In practice I have found that the very best and most efficacious absorbent material that may be used for this purpose is ordinary coal-ashes, a quantity of which placed in the bottom of the fuel-pan will absorb the liquid hydrocarbon, which may then be readily ignited. The combustion being supported by the air entering through the top or cap plate, assisted by the usual draft in the stove, will cause the flames emitted through the openings 3 and in the case of the construction shown in Figs. 1 and 2 through the top of that portion of the pan which projects laterally from the lower end of the burner-tube to be projected in the direction of the flues of the stove, which will carry off any soot, smoke, or other visible products of combustion.

The incombustible residue, which in a great many crude-oil burners as now ordinarily constructed has been the source of considerable annoyance, would become incorpo-

rated with the ashes in the bottom of the fuel-pan, which may from time to time be readily cleaned out and disposed of.

I desire it to be understood that while I have in the foregoing described a simple and preferred construction of my invention I do not limit myself with regard to the structural details of the same, but reserve the right to any changes, alterations, and modifications which may be resorted to without departing from the spirit and scope of my invention or sacrificing the utility of the same.

Having thus described my invention, I claim—

15 A hydrocarbon-burner consisting of a vertically-slotted cylinder provided at its lower end with a concave closure extended later-

ally and open in its upper side to form a fuel-pan, said cylinder being provided at its upper edge with a laterally-extending annular 20 flange engaging the griddle-hole of a cook-stove, in combination with a detachable cover-plate for said cylinder, said cover-plate being provided with an annular series of perforations and a central perforation, and 25 a fuel-feed pipe extending downwardly through said central perforation.

In testimony that I claim the foregoing as my own I have hereto affixed my signature in the presence of two witnesses.

HENRY H. ASHLOCK.
